LEIF HARTVIG JOHANSEN, OF OSLO, NORWAY

DISPENSING APPARATUS FOR SOAP POWDER AND THE LIKE

Application filed February 17, 1927, Serial No. 169,050, and in Norway April 27, 1926.

This invention relates to apparatus for dispensing of soap powder and the like and consists of arrangements by means of which a quantity of powder by opening of the outlet valve located at the lower end of the container is being conveyed towards the outlet and pressed out through the same, while the lower part of the container is thus shaped that no or only insignificant quantities of powder will fall out when the valve is at rest in the open position.

Apparatus according to the invention are in known manner provided with an outlet or delivery valve the spindle of which is carried into the container where it is guided and preferably the spindle is under spring action so as to normally keep the valve in the closed position. According to the invention the spindle is within the container provided 20 with a plate or other driver which at the downward movement of the spindle conveys a quantity of the powder towards the outlet and through the same. In order to prevent the powder from falling out when the valve 25 is at rest in the open position the lower part of the container is made conical or the like with such slope of the walls that the powder will bridge over between the walls and the spindle; thus being discharged only under 30 the influence of the said plate or driver on the spindle.

Preferably the opening stroke of the valve is limited by the said plate or driver thereby that the same abuts against the walls of the 35 container. In this case the stroke of the valve and thereby the quantity of the powder delivered for each stroke may be adjusted by adjusting the relative position of the plate or driver and the valve on the spindle.

40 In the accompanying drawing an embodiment of the invention is shown by way of example. Both figures show vertical sections of an apparatus, Fig. 1 with the valve in the closed position and Fig. 2 with the valve in the fully opened position.

1 is the container, the lower part 2 of which is shaped conically. 3 is the outlet valve mounted on the spindle 4 which is carried into the container where it is guided in the tube 5 which is secured within the container

by means of arms 6. The valve is kept in the closed position by means of the helical spring 7 lying protected within the tube 5 and abutting against a plate 8 secured to the spindle and an abutment 8^a located at 55 the lower end of the tube 5. The valve is opened by means of the arms 9 secured to the valve spindle or to collar or ring 10 in extension of the same.

At a suitable height above the outlet the 60 spindle is provided with a plate or driver 11 which at the movement of the spindle downwards carries a quantity of powder against the outlet and presses it through the same. When the spindle is at rest or moving 65 upwards the powder will, as described above, bridge over between the sloping walls of the container and no or only quite inconsiderable quantities of powder will fall out.

In the embodiment shown in the drawing 70 the opening stroke of the valve is limited by the plate or driver 11 which abuts against the walls of the container above the outlet and thereby closes the same from the inside. For adjusting of the stroke of the valve, the 75 quantity of powder to be delivered for each stroke, the valve 3 is screwed on spindle 47 so that it may be displaced on the same and secured by a counter nut or by other means, whereby the said collar or ring 10 may serve 80 as counter nut.

Having now particularly described and ascertained the nature of my said invention and in what manner the same is to be performed, I declare that what I claim is:

Apparatus for dispensing soap powder and the like comprising in combination a container having at its lower part a discharge opening, the walls of said opening constituting a valve seat, a movable valve stem passing down from the interior of the container out through said opening, said valve stem having a clear annular space between it and the opening edge, a guide for said stem arranged inside the container at a considerable distance above the discharge opening so as to leave an unobstructed space around the said stem between the guide and opening, a valve attached to the stem outside the container 90 and cooperating with the valve seat at the 95 tube 5 which is secured within the container and cooperating with the valve seat at the 100

discharge opening, a collar attached to the valve stem under the guide inside the container and operating as an agitator, means for normally retaining the valve stem in a definite resting position, the lower portion of the container being formed with smooth conical interior walls at an inclination steeper than the angle of friction of the powder, said inclination being constant and continuous down to the edge of the discharge opening.

5 In testimony whereof I hereunto affix my signature.

LEIF HARTVIG JOHANSEN.
